HAND STAPLER OR SIMILAR ARTICLE

Herbert W. Marano, Brooklyn, N. Y., assignor to Wilson Jones Company, Chicago, Ill., a corporation of Massachusetts

Application April 27, 1950, Serial No. 9,522

Term of patent 14 years

(Cl. D74—1)

To all whom it may concern:

Be it known that I, Herbert W. Marano, a citizen of the United States and a resident of Brooklyn, New York, have invented a new, original, and ornamental Design for Hand Stapler or Similar Article, of which the following is a specification, reference being had to the accompanying drawing, forming a part hereof, in which

Figure 1 is a side elevational view of a hand stapler or similar article, showing my new design;

I claim:

The ornamental design for a hand stapler or similar article, as shown.

HERBERT W. MARANO.
